CLAIM

We claim the ornamental design for a WALL SCONCE as shown and described.

DESCRIPTION

FIG. 1 is a first perspective view of a Wall Sconce according to our new design;

FIG. 2 is a second perspective view thereof;

FIG. 3 is a front view thereof;

FIG. 4 is a rear view thereof;

FIG. 5 is a first side elevation view thereof;

FIG. 6 is a second side elevation view thereof, opposite the first side elevation view;

FIG. 7 is a first plan view thereof;

FIG. 8 is a second plan view thereof, opposite the first plan view;

FIG. 9 is a perspective view of the Wall Sconce, shown in use attached to a wall;

FIG. 10 is another perspective view of the Wall Sconce, shown in use attached to a wall in an alternate orientation. The elements shown in broken lines form no part of the claimed design.
